UNITED STATES PATENT OFFICE.

EDWARD C. CORADO, OF MONTREAL, QUEBEC, CANADA

LAMPLIGHTER.

1,334,522

Specification of Letters Patent. Patented Mar. 23, 1920.

Application filed May 23, 1919. Serial No. 299,362.

To all whom it may concern:

Be it known that I, EDWARD CHARLES CORADO, a subject of the King of Great Britain, and residing in the city of Montreal, Province of Quebec, Dominion of Canada, have invented certain new and useful Improvements in Lamplighters; and I do hereby declare that the following is a full, clear, and exact description thereof.

10 This invention relates to a device for lighting kerosene and other lamps in exposed places, such as for instance, on railway switches or carried about in the open air as is the case with the signal lamps used 15 on railways.

The invention has for its object to provide a lamp lighter in which a match may be set without being ignited and only struck after having been introduced into the lamp 20 where it is sheltered from the wind.

To this end the invention consists of a lamp lighter having a match scratcher at one end, a match carrier with means for holding the match when sprung in bearing 25 relation with the scratcher and means for projecting the carrier toward the scratcher to scratch the match and hold the same while projecting beyond the scratcher. More specifically stated my improved lighter 30 comprises a tubular case having slidably mounted therein a match carrier which is adapted to be projected to a limited extent through the case by a spring, and a detent preferably in the form of a trigger retains 35 the carrier against movement under the action of the spring. A manually operated releasing member engaging the spring and when operated compressing it in order that upon the detent being released the match 40 carrier will be shot forward. The case carries at its end opposite to the manually operated member a scratcher diagonally intersecting the path of the end of the match and disposed in position to cause the tip of 45 the match to be scratched upon it, such scratcher being adapted to accommodate the match as it is set in place in its carrier and necessitate that such match be sprung against the scratcher.

50 If desired, the match carrying end of the lighter may be used with both forms of devices for projecting the match against the scratcher, without departing from the spirit of my invention.

55 For full comprehension of my invention reference must be had to the accompanying

drawings in which similar reference characters indicate the same parts, and wherein:

Figure 1 is a side elevation of my improved lamp lighter;

Fig. 2 is an axial sectional view thereof taken on line 2—2 Fig. 1;

Fig. 3 is a side elevation taken at right angles to Fig. 1, and illustrating the match carrier in its projected position; and

Fig. 4 illustrates a switch lamp with my improved lighter in use.

The case *b* of my improved lamp-lighter is tubular with one end portion partially cut away to present an opening *c* to accommodate the fingers when the match is being set in place and removed. This cut-away end of the tube has a longitudinally split collar *d*, the edges of which are cut obliquely and circumferentially slotted as at *e* in order 70 that when brought together the interior of the collar will present a diagonal serrated face *f*; while the end portion *b'* of the tube near the collar serves as a guide beneath 75 which the sulfur end of the match is held before being scratched, as will be presently shown.

A match carrier consists of a tube *g* within the case and carrying a fork *h* rigidly secured thereto and bent outwardly, while a 80 socket *i* for the butt of the match is also rigidly secured at the end of this tube. The relative positions of these parts, the 85 socket, fork and guide *b'* are such that the butt of the match may be first inserted into 90 the socket and rested in the fork after which the head of the match is sprung into place, bearing upon the inner side of the guide *b'*, the opening *c* in the case being elongated on one side as at *j* to permit the setting of the 95 match in place. The opposite end of the carrier tube *g* has a pin *k*, the end of which projects through a slot *m* in the case and is 100 preferably in the form of a pawl *n*. This pin also serves as a means for connecting one 105 end of a helical spring *o*, the opposite end of which bears against a cap *p* on the outer end of a tube *q* adapted to be slidably carried within the case and between it and the match carrier *g*. A collar *r* having diametrical finger-hold projections *s* is rigidly mounted on the case and a spring *t* encircling the tube *q*, bears between the collar *r* and a thumb rest *p* at the end of this tube 110 *q*. The detent, which is in the form of a trigger is indicated at *v*, and it is pivoted as at *w* to a collar *x* mounted rigidly on the

case, while its end has a tooth γ which has the properties of a latch imparted to it by a spring α .

The particular inclined abrading surface 5 against which the head of the match rubs has the effect of causing the degree of abrasion to increase as the match progresses across the surface owing to the increased resistance offered by the incline; and considerable advantage is obtained from the fact 10 that the tip and not the side of the head of the match is scratched. Another advantage is that the match is held in place by its own resilience and cannot fall from the holder 15 when the latter is inserted into the lamp, thus avoiding the danger of exploding the lamp by the match falling from the holder in the chimney or on top of the oil tank. In my lamp lighter the match is held firmly 20 in place until removed by hand while the accommodation for the fingers presented by the cut-away portions c and j affords facility for setting the match in place and removing it when burnt. The particular form 25 of the serrations of the match scratching face f causes it to clean itself because the particles adhering to the serrations after each match is scratched are cleared off by the particles from the ignition of the next 30 match.

Operation.

When it is desired to light a lamp in an exposed place the match is first sprung into 35 place as shown in Fig. 2.

The device is held in the hand with the thumb resting on the thumb, and two fingers taking hold of the finger holds s , by closing 40 the hand the springs o and t are compressed, the lamp is then opened and the match charged end of the lighter inserted into it as shown in Fig. 4 and held close to the wick; the trigger v is then sprung which 45 releases the pawl n and allows the spring o to project the match across the face of the scratcher, thus lighting it, and bringing the lighted end into contact with the wick.

In this manner a lamp may be lighted, however it may be exposed and whatever 50 may be the weather, without the necessity of using more than one match, and consequently wasting the time required without my invention to finally insert a lighted match into the lamp and bring it into effective proximity with the wick.

What I claim is as follows:

1. A lamp lighter comprising a case in the form of a tube having a collar at one end, such collar presenting an oblique face 55 transversely serrated, the portion of the case

adjoining the collar and in line with the serrated face being cut away to present an opening through which the end of the match may be inserted laterally; a carrier slidably within the case and carrying a socket for holding the butt of the match and a fork on which the match may be sprung when inserted; and means for projecting the match carrier through the case for the purpose of igniting the match and causing it to project 60 beyond the end of the lighter.

2. A lamp lighter comprising a case in the form of a tube having a collar at one end, such collar presenting an oblique face transversely serrated, the portion of the case 65 adjoining the collar and in line with the serrated face being cut away to present an opening through which the end of the match may be inserted laterally; a tube slidably within the case and carrying a socket for the butt 70 of the match and a fork on which the match may be sprung when inserted; means for projecting the match carrying tube through the case, such means consisting of a tubular member located between the case and the 75 inner tube, and having a thumb rest at its outer end, a helical spring within the tubular member and bearing between the end of the inner tube and the thumb rest, a pin carried by the inner tube and projecting 80 therefrom through the tubular member and case, the said tubular member and case being slotted to accommodate the said pin, and a trigger for engaging the pin and retaining the inner tube.

3. A lamp lighter consisting of a case with a diagonal match scratching member having oblique serrations extending completely through the member and means for carrying the match in tensional relation with the 90 scratching member and whereby the match may be scratched across the serrations and held projecting beyond the lighter.

4. A lamp lighter having a fixed match scratcher at one end, a match carrier with 95 means for springing the match transversely to the direction in which it is to be projected, into bearing relation with the scratcher, and means whereby the carrier is projected to scratch the match across the 100 scratcher and held the same projecting beyond the scratcher.

In testimony whereof I have signed my name to this specification in the presence of two witnesses.

EDWARD C. CORADO.
